METHOD AND APPARATUS FOR CONTINUOUSLY PLATING IRREGULARLY SHAPED OBJECTS

Oliver F. Davis, Troy, and Hans G. Belitz, Dayton, Ohio, assignors to The Commonwealth Engineering Company of Ohio, Dayton, Ohio, a corporation of Ohio

Application August 25, 1949, Serial No. 112,308

10 Claims. (Cl. 117—50)

1

This invention relates to the art of the deposition of metals. More particularly, it relates to the coating of small metal objects of irregular shape. Still more particularly it relates to the plating of objects by the deposition of metal from readily decomposed metal bearing compounds and apparatus for carrying out the process.

Depositing of thin films of metals such as iron, nickel, cobalt, and so forth, upon metal bases has been accomplished in the past by enclosing an object to be plated in a chamber, charging the chamber with a decomposable metal-bearing gas and heating the object to the decomposition temperature for said metal-bearing gas.

In the only process of which applicants have knowledge, wherein an object is moved in the plating zone, the material is thin metal sheet. This flat material is brought to the gas decomposition temperature by resistance heaters placed on the underside of the sheet. The upper side of the sheet is exposed to the decomposable gases, and a metallic coating is deposited upon only one side of the metal sheet. This metal sheet is brought into and out of the plating chamber by passing the sheet through a water bath which acts as a seal for the gas chamber.

The above described operations have many disadvantages, chief of which was the discontinuity of the processes other than the last described.

In the latter operation continuous plating was only possible upon one side of flat strips. In addition, these strips were brought into the plating chamber through a liquid sealing bath, which bath had the effect of wetting the surface of the metal and leaving enough liquid on the surface to interfere with good metal deposition.

It is an object of this invention to overcome the disadvantages and limitations of the processes known heretofore.

It is another object of this invention to provide a process which is continuous.

It is a still further object of this invention to provide a process to plate objects other than flat surfaces on a continuous basis.

It is another object of this invention to provide a process wherein objects are chemically cleaned and plated and the coating rendered ductile by heating in a continuous operation which may be handled with a minimum of labor.

A still further object of this invention is to provide apparatus which allows continuous movement of objects into the plating zone without passing through a metal wetting seal.

2

Another object of this invention is to provide a new style lock for plating chambers which allows ingress of objects without danger of escape of toxic gases into the outside atmosphere.

It is another object of this invention to provide a process which may be operated under either positive or negative pressure conditions.

Another object is to provide apparatus having a single chamber divided into segments by a simple divider mechanism which, in conjunction with control of gas pressure, seals the apparatus against leakage of plating gas.

Other and more specific objects and advantages will be apparent to one skilled in the art as the following description proceeds.

In this new process small objects are mounted in a fixture carried by a continuous belt. This fixture supports the objects in an extended position, so that in their early travel they project downward into solution baths, then reverse their course and project upwardly, while passing through plating and annealing chambers.

In this way it is possible to get compact equipment operable with a minimum of costly manual labor. It also provides means for counter-current movement of objects and plating gas through a plating chamber.

The atmosphere in the plating chamber may be maintained either at pressures above atmospheric or at pressures below atmospheric maintained by suction or vacuum drawn on the chamber.

It is possible in this new process and apparatus to utilize a gaseous atmosphere formed by mixing an inert gas with the vapors of a volatile metal compound or by atomizing a liquid metal compound into a blast of hot inert gas or other equivalent method.

Thus, it is possible to use volatile metal compounds which are or can be converted into vapors either by themselves or by making solutions of the metal compound and highly volatile solvents.

When introducing the metal compounds the vapors are generally diluted with an inert gas, carbon dioxide, helium, nitrogen, hydrogen, the gaseous product of controlled burning of hydrocarbon gases free of oxygen, and the like, have been utilized as a carrier medium as well as being the inert gas medium utilized in the non-plating operation.

In some instances the use of hydrogen is preferred, as for example, in the cleaning anneal chamber where its ability to act as a reducing

agent may be put to advantage to remove the oxide film or rust from iron wire.

Metals to be deposited may be introduced as gaseous metal carbonyls or vaporized solutions of certain of the metal carbonyls in readily vaporizable solvents (for example, petroleum-ether), also nitroxyl compounds, nitrosyl carbonyls, metal hydrides, metal alkyls, metal halides, and the like.

Illustrative compounds of the carbonyl type are nickel, iron, chromium, molybdenum, cobalt, and mixed carbonyls.

Illustrative compounds of other groups are the nitroxyls, such as copper nitroxyl; nitrosyl carbonyls, for example, cobalt nitrosyl carbonyl; hydrides, such as antimony hydride, tin hydride; metal alkyls, such as chromyl chloride; and carbonyl halogens, for example, osmium carbonyl bromide, ruthenium carbonyl chloride, and the like.

Each material from which a metal may be plated has a temperature at which decomposition is complete. However, decomposition may take place slowly at a lower temperature or while the vapors are being raised in temperature through some particular range. For example, nickel carbonyl completely decomposes at a temperature in the range of 375° F. to 400° F. However, nickel carbonyl starts to decompose slowly at about 175° F. and, therefore, decomposition continues during the time of heating from 200° F. to 380° F.

A large number of the metal carbonyls and hydrides may be effectively and efficiently decomposed at a temperature in the range of 350° F. to 450° F. When working with most metal carbonyls we prefer to operate in a temperature range of 375° F. to 425° F.

Maintenance of the object at temperatures generally in the decomposition range is readily accomplished by causing the object to be heated by infrared rays or by induction heating. The advantage of this type of heating is its ready control within the temperature ranges utilized in the process. These temperatures generally range from 350° F. to 450° F. in the plating zones and from 800° F. to 1200° F. in the annealing zones.

Preparatory to coating the objects, the objects may be cleaned by employing conventional methods used in the art, comprising simple coatings through electrochemical cleaning by moving the object through baths of alkali or acid electrolyte.

When the objects are metal they may be pickled with hydrochloric, sulfuric or nitric acid, or a combination of acids, and the object then thoroughly rinsed and washed prior to further treatment.

The invention will be more clearly understood from the following description of one embodiment of the apparatus and its mode of operation.

In the drawings:

Figure 1 is a perspective view of the equipment with portions cut away to disclose the internal apparatus arrangement;

Figure 2 is a diagrammatic illustration of the process steps carried out in the apparatus of Figure 1;

Figure 3 is an elevational view partly in section of the fixture and the shank of an object to be plated;

Figure 4 is a view along the line 4—4 of Figure 3;

Figure 5 is a perspective view of the continuous belt and the supports for the fixtures;

Figure 6 is a plan view of the upper plating per-

tion of the apparatus with the roof cut away over various locks and chambers;

Figure 7 is a view along the line 7—7 of Figure 6;

Figure 8 is a perspective view of the drive and continuous belt path arrangement whereby objects are carried through various baths;

Figures 9 and 10 are enlarged views of the resilient partition, gas locks showing the progress of an object through said lock; and

Figure 11 is an elevational view of the foot control for the apparatus actuated by the operator loading and unloading fixtures.

Referring to the drawings in detail, first in connection with Figures 1 and 5, there is shown objects 10, in this case illustrated as heads of a golf club.

Objects 10 are mounted on fixtures 11 which are carried by a continuous belt 12 such as a chain belt. Belt 12 is supported and actuated by sprockets 13 and 14 mounted on framework 15.

Framework 15 intermediate the end sprocket forms a base for support of the bottom series of units indicated at 16, more details of which will be given upon reference to Figure 2, and an upper series of chambers or conduits indicated at 17, more details of which will be given with relation to Figures 6 and 7.

Sprocket 13 is in an enclosed chamber 18 which is provided with inlet and outlet ducts 19 and 20 for introduction and removal of hot air. Sprocket 13 is the primary drive unit for the belt 12 and is driven through drive shaft 21 and gears 22 from a source of power 23 such as an electric motor.

Drive shaft 21 also carries a gear 24 which meshes with a gear 25 on the shaft 26. As indicated in Figure 8 shaft 26 carries gears 27 which drive gears 28 which are mounted on shaft 29 for directing and driving the chain belt 12 through the series of tanks of unit 16.

As indicated in Figure 2 unit 16 is a series of tanks 30 to 36, inclusive, enclosed in a housing 37. Housing 37 carries the bearings 38 and 39 for shafts 26 and for shafts 40, respectively.

In the upper portion of housing 37 is mounted the chamber unit indicated at 17. This unit consists of a number of compartments, herein illustrated with three compartments 41, 42 and 43.

As indicated in Figure 2, compartment 41 is adapted for heating the objects in an inert atmosphere. Compartment 41 is closed at the ends with locks 44 and 45 and the lock partition framework 44a and 45a, respectively, and has a glass top side 46 through which infrared heating rays may be directed from lamps 47. Compartment 41 is provided with gaseous inlet and outlet ducts 48 and 49.

Compartment 42 is similar to compartments 41 and 43, being separated therefrom by locks 45 and 50. For safety in preventing leakage of toxic carbon monoxide, compartment 42 is of double construction as illustrated in Figure 7.

The compartment as illustrated, consists of a rectangular cross sectional conduit 51 mounted in unit 17 framework. Within the conduit 51 is a smaller conduit 52 of rectangular cross section. Each of these conduits is provided with a glass top when infrared heating is utilized.

Conduit 52 is the plating chamber through which belt 12 conveys objects 10. Conduit 52 is provided with inlet and outlet gas conduits 53 and 54.

The space between conduits 51 and 52 is pro-

vided with ingress and egress means for circulation of inert gas.

The housing 37 is provided with a glass top 55 over the compartment 42. Heat rays are directed into compartment 42 from infrared lamps 56 suspended from the light fixture 51.

Compartment 43 is closed at its further end by lock 60 and its partition framework 60a. This compartment is provided with gas inlet and outlet conduits 61 and 62.

The locks permitting passage of solid objects carried by the belt are further illustrated in Figures 9 and 10 with reference to lock 50. Lock 50 consists of spaced walls 70 and 71 having resilient arms 72, 73, 74 and 75 extending therebetween.

Each arm is made up of two half sections, for example, 72a and 72b. Each arm is laterally spaced to provide air chambers, only two of which are in communication with an object passing through one arm.

As illustrated in Figure 9 when an object 10 starts through a lock it contacts arm 72 at its center or separation point. By the time the object is contacting arms 74 (Figure 10) the object is clear of arm 72 permitting that arm to close and thus prevents ingress of air. Thus, there are two or more arms closing the entrance or exit to gas transfer during the passage of an object through these locks.

The object passing through a lock must be securely fixed to its support. A detailed illustration of a fixture for securing an object is shown in Figures 3 and 4.

The fixture 11 consists of a base 80 secured to two arms 81 and 82 of belt 12. Mounted on the base 80 is a block 83 having a vertical arm 84 and spaced therefrom a vertically extending pin 85. Arm 84 is adapted with a threaded port 86 to receive the wing screw 87.

Intermediate the arm and pin there extends vertically companion projections 88 apertured as at 89 to receive a pivot pin 90. Pivotally mounted on the pin 90 is an angled contact arm 91 adapted with a bifurcated tongue 92 for clamping objects 10 securely on pin 85 when engaged by wing screw 87.

In the operation of this equipment the speed of movement of belt 12 determines, for example, the length of the plating chamber for the deposition of a fixed thickness of coating on the object having a certain surface area.

Other variables related to deposition of metal are present in the process, for example, the concentration of carbonyl vapors fed to the plating chamber. It will be understood, therefore, that the following description merely is illustrative of the conditions which are operative for a given belt speed and for objects of a given size and for plating a specific depth of coating, and not by way of limitation.

Golf club heads are mounted on fixtures 11 of belt 12 as shown in Figure 2 at the loading zone. The belt 12 may move at the rate of 2 feet per minute per foot of plating chamber.

The belt carries the head through a degreasing chamber 36 where it is washed with grease solvents such as light naphtha. The belt then moves the object through a caustic bath in tank 35, which may consist of 4 normal sodium hydroxide solution. The belt then moves the object through hot and cold water rinses in series.

Following rinsing the golf club heads are dipped into a pickling bath in tank 32, as for example, in 4 normal sulfuric acid solution. The

heads then travel in and out of the wash tanks 30 and 31 and are dried in chamber 18 where a clean hot air at a temperature of approximately 300° F. is circulated.

5 The golf head then passes through lock 44 into compartment 41 maintained with an inert atmosphere of carbon dioxide gas under a pressure of about 30 pounds per square inch gage.

10 While passing through compartment 41 the golf club head is heated to approximately 390° F. The heated head then passes through lock 45 into the plating compartment 42. This compartment is fed a mixture of carbon dioxide gas and metal carbonyl, such as nickel carbonyl, at 15 a gas rate in the range of 5 to 10 cubic feet per minute with the, for example, nickel carbonyl content of approximately 7 ounces of carbonyl per cubic foot of carbon dioxide.

The heads may be plated to a depth of .002 inch in a 30 second plating interval. The plated head moves through lock 50 into the cooling compartment 43 where the heads cool in a cold inert gas atmosphere, usually carbon dioxide gas, maintained under 30 pounds per square inch gage.

25 When a long plating chamber is used and the belt therefor speeded, the belt may be driven by a motor electrically connected for momentary interruption of drive to a foot pedal 93 as illustrated in Figure 11, which is under the control of the operator at the loading zone.

It will be understood that while the method and apparatus disclosed and described herein illustrate a preferred form of invention, modifications can be made without departing from the spirit of the invention, and that modifications that fall within the scope of the appended claims are intended to be included herein.

We claim:

40 1. A method of plating objects by the deposition of metal from heat-decomposable metal compounds which comprises the steps of conveying said objects to be plated while maintained in spaced relationship with respect to each other through a plating chamber, circulating a gaseous metal compound through said chamber, heating said objects by contacting the same with a hot gaseous medium while the same are conveyed therealong and prior to entering said chamber, thereafter moving said objects into said plating chamber and subjecting the same to a temperature sufficient to cause decomposition of said gaseous metal compound in said chamber and deposition of metal on said objects while the same are conveyed therealong through said plating chamber, and subjecting said objects to an inert gaseous cooling medium after passage of the same from said chamber and before said objects are conveyed into the open atmosphere.

45 2. A method of plating objects by the deposition of metal from heat-decomposable metal compounds which comprises the steps of conveying

50 said objects to be plated through a plating chamber, circulating a gaseous metal compound through said chamber, heating said objects by

55 contacting the same with a hot gaseous medium prior to conveying the same into said chamber to a temperature sufficient to cause decomposition of said gaseous metal compound in said

60 chamber and deposition of metal on said objects while the same are conveyed therealong through said plating chamber, conveying said heated objects into said plating chamber to cause de-

65 composition of said gaseous metal compound and deposition of metal on said objects, and subject-

70 ing the same to an inert gaseous cooling medium after passage of the same from said chamber and before said objects are conveyed into the open atmosphere.

75

ing said objects to an inert gaseous cooling medium after passage of the same from said chamber and before said objects are conveyed into the open atmosphere, said heating being carried out in an inert atmosphere.

3. A method of plating objects by the deposition of metal from heat-decomposable metal compounds which comprises the steps of conveying said objects to be plated while maintained in spaced relationship with respect to each other through a plating chamber, circulating gaseous material through said plating chamber at least a portion of which comprises a heat-decomposable metal compound, heating said objects by contacting the same with a hot inert gaseous medium prior to entering said plating chamber, said objects being heated to a temperature sufficient to cause the decomposition of said gaseous metal compound in said plating chamber and deposition of metal on said objects while the same are conveyed through said chamber, said gaseous metal compound being selected from the group consisting of the gaseous metal carbonyls of chromium, nickel, iron, molybdenum, cobalt and mixtures thereof, and subjecting said objects to an inert gaseous cooling medium after movement of the same through said plating chamber and before conveying said plated objects into the open atmosphere.

4. A method of plating objects by the deposition of metal from heat-decomposable metal compounds which comprises the steps of conveying said objects to be plated while maintained in spaced relationship with respect to each other through a plating chamber, circulating gaseous material through said plating chamber at least a portion of which comprises a heat-decomposable metal compound, heating said objects by contacting the same with a hot inert gaseous medium prior to entering said plating chamber, said objects being heated to a temperature sufficient to cause decomposition of said gaseous metal compound in said plating chamber and deposition of metal on said objects while the same are conveyed through said chamber, said gaseous metal compound consisting of nickel carbonyl, and subjecting said objects to an inert gaseous cooling medium after movement of the same through said plating chamber and before conveying said plated objects into the open atmosphere.

5. A method of plating objects by the deposition of metal from heat-decomposable metal compounds which comprises the steps of conveying said objects to be plated while maintained in spaced relationship with respect to each other through a plating chamber, circulating gaseous material through said plating chamber at least a portion of which comprises a heat-decomposable metal compound, heating said objects by contacting the same with a hot inert gaseous medium prior to entering said plating chamber, said objects being heated to a temperature sufficient to cause decomposition of said gaseous metal compound in said plating chamber and deposition of metal on said objects while the same are conveyed through said chamber, said gaseous metal compound consisting of chromium carbonyl, and subjecting said objects to an inert gaseous cooling medium after movement of the same through said plating chamber and before conveying said plated objects into the open atmosphere.

6. In a method of plating objects by the deposition of metal from heat-decomposable metal

compounds comprising conveying said objects to be plated while heated through a chamber in which is circulated a heat-decomposable metal compound, the improvement which consists in preheating said objects to a temperature sufficient to decompose said heat-decomposable metal compound in the plating chamber by subjecting said objects while the same are conveyed along toward said plating chamber to an inert hot gaseous medium, thereafter conveying said pre-heated objects into said plating chamber to cause decomposition of said heat-decomposable metal compound and deposition of metal on said objects, and cooling the plated objects after passage of the same from said chamber by subjecting said objects to an inert gaseous cooling medium.

7. In apparatus for continuously plating objects of irregular shape, the combination comprising an endless belt; fixtures carried by said belt for holding objects thereon in spaced relation; guides for said belt directing its travel through a plating chamber; mechanical locks limiting gaseous movement at the inlet and outlet of said chamber; said locks comprising spaced flexible walls having a separable portion therein for the passage therethrough of objects to be plated; heating means for said objects; and inlet and outlet means for introducing and removing gaseous material from said chamber.

8. In apparatus for continuously plating objects of irregular shape, the combination comprising an endless belt; fixtures carried by said belt for holding objects thereon in spaced relation; guides for said belt directing its travel through conduits joined in series; mechanical locks limiting ingress and egress of gaseous material from each conduit; said locks comprising spaced flexible walls having a separable portion therein for the passage therethrough of objects to be placed; heating means associated with one of said conduits; and inlet and outlet means for introducing and removing gaseous material from each conduit.

9. In apparatus for continuously plating objects the combination comprising an endless belt; fixtures carried by said belt for holding objects thereon in spaced relation; a series of tanks; guides for said belt directing the belt in a path carrying the objects into and out of each tank; a drying chamber; means in said drying chamber for reversing the direction of said belt; conduits adapted to have the belt travel therethrough in series; mechanical locks limiting ingress and egress of gaseous material from each conduit; said locks comprising spaced flexible walls having a separable portion therein for the passage therethrough of objects to be plated; heating means associated with one of said conduits; and inlet and outlet means for introducing and removing gaseous material from each conduit.

10. In apparatus for continuously plating objects the combination comprising an endless belt; fixtures carried by said belt for holding objects thereon in spaced relation; guides for said belt directing its travel through an elongated chamber; mechanical locks at the inlet and outlet of said chamber and at positions dividing said chamber into segments, said locks consisting of a series of spaced flexible walls divided along the central vertical axis; heating means associated with the segments adjacent the inlet; and

9

conduit means for introducing and removing gaseous material from each chamber segment.
